UNITED STATES PATENT OFFICE.

GEORGE W. KNOX, OF PHILADELPHIA, PENNSYLVANIA.

FLOAT FABRIC.

No. 873,378.

Specification of Letters Patent.

Patented Dec. 10, 1907.

Application filed July 9, 1906. Serial No. 325,218.

To all whom it may concern:

Be it known that I, GEORGE W. KNOX, a citizen of the United States, residing in the city and county of Philadelphia, State of Pennsylvania, have invented a new and useful Improvement in the Manufacture of Float Fabrics, of which the following is a specification.

It is well known that fabrics of the order 10 of madras, etc. have been formed of warp and weft threads and warp floats which latter produce ornamental effects on the fabric and are cut or sheared off close to the terminals of said effects, the portions of the floats 15 so cut or sheared off being lost as warps or considered as waste.

The object of my invention is to utilize the floats employed to form such fabrics for the production of ornamental effects in a plurality 20 of fabrics. To this end I form in the same loom, two blank fabrics of warp and weft threads and float threads and as each fabric is being made I run the float threads employed to produce figures or figured effects 25 on one fabric to the opposite fabric where they are employed to produce figures or figured effects in the latter and then return to again produce figures or figured effects on the first narrow fabric and so the work continues, the float threads between the fabrics 30 being duly cut, thus separating the two fabrics, while the float threads at the terminals of the figures or figured effects on the fabrics are duly trimmed said figures or 35 effects being those of the float threads thrown into the fabrics.

Figures 1 and 2 represent face views of a plurality of fabrics embodying my invention. Fig. 3 represents a horizontal section of a 40 portion of the two fabrics on an enlarged scale in the course of manufacture. Fig. 4 represents a view of a portion of one of the fabrics showing float threads having been employed to form a float figure or figured effect in said fabric and to be thrown into the opposite fabric to form a float figure or figured effect therein.

Similar numerals of reference indicate corresponding parts in the figures.

50 Referring to the drawings:—A and B designate two pieces of fabric produced in accordance with my invention, each of the same being produced of warp threads C, weft threads

D and float wefts E, the latter being adapted to form the figures or figured effects F, F'. 55

In carrying out my invention, I form two fabrics in the same loom as blanks, each composed of warp threads C, weft threads D, which effects may be different. I employ a jacquard whereby the float wefts, after forming a figure or figured effect, as at F', on the fabric A, are passed to the fabric B where they are woven in said fabric B to form the figure or figured effect F; after which they are again passed to the fabric A and woven 60 with the latter to form another figure or figured effect as at F', it being evident that the jacquard may be so operated as to produce different patterns of figures or figured effects in the two fabrics or the same patterns, 65 it being noticed that the float wefts instead of being cut off and lost as threads or considered as waste are utilized to form the figures or figured effects of the two fabrics, as has been stated. The small portions of the 70 float wefts between the two fabrics are cut or severed thus dividing the fabrics, said portions then being trimmed at the terminals of the figures or figured effects, thus finishing the latter and the two fabrics as such are 75 completed, there having been a great saving in the manufacture of the two fabrics in stock and time.

Having thus described my invention, what I claim as new and desire to secure by 80 Letters Patent, is:

1. A fabric blank composed of a plurality of fabrics, each having a plain figured surface produced from warp and weft threads and floating wefts, the latter extending from one 90 fabric to the other and woven with the warp and weft threads to produce figures upon one fabric only at a time.

2. A fabric blank composed of a plurality of fabrics, each having a plain figured surface 95 produced from warp and weft threads and floating wefts, the latter extending from one fabric to the other and woven with the warp and weft threads to produce figures upon one fabric only at a time, said floating wefts joining the two fabrics and extended at right angles to the warp threads. 100

GEORGE W. KNOX.
